UNITED STATES PATENT OFFICE

165,854

CIRCULATOR FAN OR SIMILAR DEVICE

Donald F. McCarron, St. Louis, Mo., assignor to Knapp-Monarch Company, St. Louis, Mo., a corporation of Delaware

Application July 1, 1950, Serial No. 10,925

Term of patent 14 years

(Cl. D26—7)

To all whom it may concern:

Be it known that I, Donald F. McCarron, a citizen of the United States and a resident of the city of St. Louis, State of Missouri, have invented a new, original, and ornamental Design for Circulator Fan or Similar Device, of which the following is a specification, reference being had to the accompanying drawing, forming a part thereof, in which:

Figure 1 is a perspective view of a circulator fan or similar device showing my new design as it appears when used as a floor fan.

The dominant features of my design reside in the portions shown in solid lines.

I claim:

The ornamental design for a circulator fan or similar device, substantially as shown and described.

DONALD F. McCARRON.
